UNITED STATES PATENT OFFICE.

CARL PFANSTIEHL, OF HIGHLAND PARK, ILLINOIS, ASSIGNOR TO PFANSTIEHL RADIO SERVICE CO., A CORPORATION OF ILLINOIS.

DIAL ADJUSTER.

Application filed July 23, 1923. Serial No. 653,171.

To all whom it may concern:

Be it known that I, CARL PFANSTIEHL, a citizen of the United States, residing at Highland Park, in the county of Lake and State of Illinois, have invented new and useful Improvements in Dial Adjusters, of which the following is a specification.

This invention relates to devices for adjusting dials and the like and is particularly adapted to be used for adjusting the dials of condensers, vario coupler and variometers of radio receiving apparatus.

It is fully described in the following specification and shown in the accompanying drawings in which:

Figure 1 is a front elevation of a dial with a dial adjuster thereon in normal inoperable position;

Fig. 2 is a similar view with the dial removed; and

Fig. 3 is a vertical section on the line 3 of Fig. 1.

The device as here illustrated is shown in connection with a condenser having a shaft 10 which is journaled in the end plate 11 of the condenser which is secured to the panel 12 by means of screws (not shown). An ordinary dial 13 is secured on the outer end of the shaft 10 by means of a screw 14. This dial is held a fixed distance from the panel 12 by means of an insulated bushing 15.

The adjuster is placed between the dial 13 and the panel 12 and comprises a flat lever 16 which is pivotally mounted near its upper end on a shouldered bolt 17 which is secured to the panel 12. The lever 16 has a slot 18 which is slidable over the bolt 17. A large opening 19 is located near the center of the lever and loosely surrounds the bushing 15. Spacing fingers 20 of wire are secured to the lever 16 at 21, the upper ends pressing against the bushing 15. Owing to the angle which the upper end of the fingers are bent pressure is exerted upon the bushing 15 which normally tends to hold the lever 16 both in the central and raised position as shown with the bottom of the opening 19 pressing against the bottom of the insulated bushing 15.

The upper end of the lever 16 is bent outwardly and downwardly and holds a small block 22 of rubber, fabric or the like. An operating knob 23 is secured to the lower end of the lever.

It will be understood from the foregoing that an approximate adjustment of the condenser may be made by moving the dial 13 by means of the knob 13^a in the usual way. When, however, a much finer adjustment is desired, the operator grasps the knob 23 drawing the lever 16 down against the action of the spring fingers 20, until the block 22 is in engagement with the dial 13. Any movement now of the knob to the right or left will cause the lever 16 to swing about the pin 17 as a pivot. Owing to the fact that the distance from the knob 23 to the pin 17 is many times as great as the distance of the pin 17 to the rubber block 22 which is in contact with the edge of the dial, a relatively large movement of the knob 23 to the right or left will cause the dial to be moved a relatively small amount.

It will be understood that this device is applicable to nearly all the devices now on the market employing dials and that by its use any dial may be given a micrometer or vernier adjustment.

While I have shown and described certain embodiments of my invention, it is to be understood that it is capable of many modifications. Changes therefore in the construction and arrangement may be made without departing from the spirit and scope of the invention as disclosed in the appended claims, in which it is my intention to claim all novelty inherent in my invention as broadly as possible in view of the prior art.

I claim:

1. An adjuster for dials comprising a lever adapted to lie between the dial and panel and having two portions extending from beneath said dial, means attached to one of said portions for making contact with said dial, means normally holding said contact means out of contact with the edge of the dial, and a pivot near the contact means about which the lever moves.

2. An adjuster for dials comprising a lever adapted to lie between the dial and panel and having two portions extending from beneath opposite sides of said dial, means attached to one of said portions for making contact with said dial, means normally holding said contact means out of contact with the edge of the dial, and a pivot near the contact means about which the lever moves.

3. An adjuster for dials comprising a lever adapted to lie between the dial and panel and having two portions extending from beneath opposite sides of said dial, a rubber member attached to one of said portions for making contact with said dial, two converging springs pressing upon the dial shaft to center the lever and hold said rubber member out of contact with the dial, and a pivot about which the lever moves.
4. An adjuster for dials comprising a lever adapted to lie between the dial and panel and having two portions extending substantially radially in opposite directions from beneath said dial, one of said portions carrying a member adapted to contact the edge of said dial when said member is moved radially toward said dial, means normally holding said member out of contact with the edge of the dial, and a fulcrum adapted to be secured near said member about which the lever swings, said lever having an opening through which the shaft of the dial projects.
5. An adjuster for dials comprising a lever adapted to lie between the dial and panel and having two portions extending substantially radially in opposite directions from beneath said dial, one of said portions carrying a member adapted to contact the edge of said dial when said member is moved radially toward said dial, means normally holding said member out of contact with the edge of the dial, and a fulcrum adapted to be secured near said member about which the lever swings.
6. An adjuster for dials comprising a lever adapted to lie between the dial and panel and having one portion extending beyond the dial by which the lever may be moved, another portion of said lever adapted to make driving contact with the dial when the last-named portion is moved in one direction by the first mentioned portion, said dial being then rotatable by motion of the lever in a plane parallel to the dial.

CARL PFANSTIEHL.
